UNITED STATES PATENT OFFICE.

JAMES L. DORWARD, OF SAN FRANCISCO, CALIFORNIA.

DESIGN FOR A NECKTIE-HOLDER.

55,553.

Specification for Design.

Patented June 29, 1920.

Application filed February 19, 1919. Serial No. 278,073. Term of patent 7 years.

To all whom it may concern:

Be it known that I, JAMES L. DORWARD, a subject of the King of Great Britain, residing in the city and county of San Francisco and State of California, have invented a new, original, and ornamental Design for a Necktie-Holder, of which the following is a specification, reference being had to the accompanying drawings forming part thereof.

The figure on the drawing is a perspective view of a necktie holder showing my new design.

I claim:

The ornamental design for a necktie holder, as shown.

JAMES L. DORWARD.
